UNITED STATES PATENT OFFICE.

STEPHEN GROVER CHAMBERS, OF OREGON CITY, OREGON.

PAPER-MACHINE COUCH ROLL.

Application filed April 11, 1923. Serial No. 631,474.

To all whom it may concern:

Be it known that I, STEPHEN GROVER CHAMBERS, a citizen of the United States, and a resident of Oregon City, county of 5 Clackamas, and State of Oregon, have invented a new and useful Improvement in Paper-Machine Couch Rolls, of which the following is a specification.

My invention relates to paper making machines, and especially to the paper forming end of the paper machines.

As is well known, paper is formed from a dilute mixture of paper stock which is passed to a moving wire belt, on which the water is 10 permitted to drain from the mixture and the pulp stock, suspended in the water is retained. The pulp stock is then passed between two couch rolls which express a substantial portion of this water from the pulp 15 stock and form the stock into a damp sheet of paper. My invention concerns these two couch rolls which, as now made, consist of two metallic rollers which are placed one above the other and the upper one is covered 20 by a woven jacket. The ends of the jacket are secured around the ends of the roll. It has been found that this jacket will tend to 25 creep rotatively on the metallic roll. It was also noticed that the middle portion of the 30 jacket would creep faster than the adjacent portions because the jacket being bent over the end of the roll exerted a greater frictional resistance to relative motion than did the straight surfaces.

The object of my invention, therefore, is to provide a means whereby the woven jacket of the top couch roll of paper machine will 35 creep uniformly in relation to the roll itself.

I attain this object by providing two dished plates, one on each end of the roll, and mounted for independent rotation with the roll, the peripheries of these disks forming substantially a continuation of the surface of the roll, but the disk being spaced slightly 40 therefrom and having no appreciable frictional bearing on the ends of the roll and being adapted to have the ends of the covering recessed thereto.

I have shown this device in the accompanying drawings, in which:

Fig. 1 is a fragmentary view of the roll having a dished plate on the end adapted to have the ends of the covering engaged therewith;

Fig. 2 is an end view of the roll shown 55 in Fig. 1 and shows how the jacket is secured around the dished plate; and

Fig. 3 is a perspective view of this dished plate which is independently mounted at the 60 end of the roll.

The roll *a* is made with a stub shaft *b* on which the roll is journaled. A ball race *c* is provided on each end of the roll *a* and the dish-shaped plate *e* is rotatably mounted on the stub shaft *b* so as to bear against the race 65 *c*. The woven jacket *f* is slightly longer than the roll *a* and the ends are crimped around the dish shaped plates *e*. The folds *g* are sewn as at *h* so as to hold the jacket taut around the roll *a*. The jacket *f* is thus 70 entirely independent of the roll *a* except that it bears against the periphery along its entire length. The rim *i* of the dished plate *e* forms substantially a continuation of the periphery of the roll *a* but is slightly spaced 75 therefrom so as not to have frictional engagement therewith. It can thus be seen that the woven jacket *f* will have a uniform frictional contact with the roll *a* along its entire 80 length and in practice it has been found that the frictional engagement of the dished plate *e* on the race *c* is negligible so that the ends of the jacket will grip the roll substantially in the same degree as the middle portion. It 85 is also to be noticed that the jacket being fastened over the plates and not being snubbed around the end of the roll will cause the jacket to be of uniform thickness throughout its entire length when in operation. This is of 90 considerable importance because the least variation in thickness of this jacket will result in a corresponding variation in thickness of the sheet of paper stock which contacts with the jacket at this point and will thus cause the wet sheet to break at the thinner portions.

I claim:

1. In a couch roll having a resilient covering, the combination of a roll provided with stub axles at its ends, a plate mounted for independent rotation about each of said axles, said plates being diametrically the same as, and constituting a continuation of the peripheral surface of, said couch roll, means for spacing the plates relatively from the roll ends so as to have no appreciable frictional bearing on such ends, the ends of the covering for said couch-roll extending beyond the ends of the roll and engaged with 100 105

2
said plate, whereby any creeping of the covering placed on the roll is rendered substantially uniform thruout its length.

5 2. In a couch roll having a resilient covering, the combination of a roll provided with stub axles of smaller diameter at its ends, a plate mounted on each of said axles and adapted for independent rotation thereon, the ends of the covering for said couch-roll 10 extending beyond the ends of the roll and engaged with said plate, whereby any creeping of the covering placed on the roll is rendered substantially uniform thruout its length.

15 3. In a couch roll having a resilient covering, the combination of a roll provided with stub axles at its ends, a dished plate mounted for independent rotation about each of said axles, the concaved portion of said dished plate facing the roll, means for positioning 20 the plates relatively to the roll ends so as to have no appreciable frictional bearing on such ends, the ends of the covering for said couch roll extending beyond the ends of the roll and engaged with said plate, whereby 25 any creeping of the covering placed on the roll is rendered substantially uniform thruout its length.

4. In a couch roll having a resilient covering, the combination of a roll provided with 30 stub axles at its ends, a dished plate mount-

ed for independent rotation about each of said axles, the concaved portion of said dished plate facing the roll, said plates being diametrically the same as, and constituting a continuation of the peripheral surface 35 of, said couch roll, means for positioning the plates relatively to the roll ends so as to have no appreciable frictional bearing on such ends, the ends of the covering for said couch-roll extending beyond the ends of the roll 40 and engaged with said plate, whereby any creeping of the covering placed on the roll is rendered substantially uniform thruout its length.

45 5. In a couch roll having a resilient covering, the combination of a roll provided with stub axles at its ends, a dished plate mounted for independent rotation about each of said axles, the concaved portion of said dished plate facing the roll, said plates being 50 diametrically the same as, and constituting a continuation of the peripheral surface of, said couch roll, the ends of the covering for said couch-roll extending beyond the ends of the roll and engaged with said plate, whereby 55 any creeping of the covering placed on the roll is rendered substantially uniform thruout its entire length.

STEPHEN GROVER CHAMBERS.
